UNITED STATES PATENT OFFICE.

HERBERT E. IVES, OF MONTCLAIR, NEW JERSEY, ASSIGNOR, BY MESNE ASSIGNMENTS,
TO WESTERN ELECTRIC COMPANY, INCORPORATED, A CORPORATION OF NEW YORK.

TRANSMISSION OF PICTURES BY ELECTRICITY.

Application filed March 2, 1925. Serial No. 12,693.

This invention relates to picture transmission apparatus and more particularly to the optical system employed in reproducing pictures transmitted by electrical means.

5 In applicant's Patents, Nos. 1,667,805 and 1,683,976, granted May 1, 1928, and Sept. 11, 1928, respectively, two forms of reproducing systems are described which are adapted for the reproduction of electrically transmitted pictures. In the first of these the reproduced pictures are composed of successive lines or traces of varying width, while in the second the successive traces are of constant width but varying in density along the trace.

10 15 The reproduced picture in both instances is composed of exposed areas, which are separate and distinct from one another and give a grained appearance to the picture.

An object of the present invention is to 20 improve the faithfulness of reproduction of pictures transmitted electrically.

Another object is to double or overlap successive exposure so as to produce a picture more nearly like the original.

25 30 35 In the attainment of these objects according to one embodiment of the invention the exposure of the recording film is controlled by a light valve which itself is energized by a carrier wave modulated in accordance with the tone values of elemental areas of the picture to be transmitted. Interposed in the light path from the light valve to the recording film is double image producing element, such as a piece of Iceland spar. The recording film moves relatively to the light valve aperture and for each exposure of the recording film a double image of the aperture is obtained. Means are also provided to produce overlapping of successive exposures.

40 45 Substantially grainless reproductions from the standpoint of the lay observer are thus obtained, the texture of the reproduction being observable only under a microscope.

Other objects and advantages of the invention will become apparent from the following description and drawings:

Fig. 1 is a diagrammatic view of an optical system embodying the present invention. Fig. 2 shows one type of optical system to 50 which the invention is applicable. Fig. 3 illustrates an enlarged portion of a picture, composed of lines of varying width. Fig. 4 illustrates the same portion produced by means of the optical system of this invention. Fig. 5 is a diagrammatic view similar to Fig.

2 embodying a modification of the invention. Fig. 6 illustrates a cross section of another type of picture as reproduced according to the system of Fig. 5. Fig. 7 illustrates a cylindrical lens as used in a further modification of the invention. Fig. 8 illustrates a cross section of a picture produced using the lens shown in Fig. 7.

Like elements in the several figures are designated by identical reference characters. 60 65

The present invention is applicable to any type of picture transmission system which reproduces pictures, writing or other electrically transmitted subjects by means of an optical system. Two suitable optical systems are disclosed in applicant's patents, referred to above. The typical optical system illustrated in Fig. 2, consists of a light source 12 and a concentrating lens 13 for focusing light upon the aperture of a light valve V 70 together with a projecting lens 19.

As shown in Fig. 2 this light valve comprises a field magnet 15 and a string shutter element 16 in circuit with a transformer 17. Carrier current signals impressed on transformer 17 cause current fluctuations in the light valve string 16 which is vibrated from side to side exposing the light aperture first on one side of the string and then on the other. Light passing the light valve shutter varies in intensity corresponding to the amplitude of the carrier wave. This light is focused on a rotating recording drum 18 by means of lens 19.

80 85 90 95 Since the string of the light valve vibrates in a direction perpendicular to the trace on the recording drum the resulting picture will be composed of lines of varying width as illustrated in Fig. 3 and more fully described in applicant's Patent No. 1,667,805 referred to above. These lines are in reality two separate exposures placed back to back as illustrated by the line B-C of Fig. 3.

In the present invention applicant includes in the optical system some means for forming a double image of the light valve aperture on the recording cylinder such as a split lens or heliometer, a bi-prism or preferably a piece of double refracting Iceland spar. In any case two separate and distinct images 100 105 will be formed close together on the recording element.

110 In forming the portion of a picture illustrated in Fig. 3 according to the present invention the recording beam of light passes

through a piece of Iceland spar 20 as shown in Fig. 1. Each image is therefore formed twice as indicated at A and A', B and B', etc., in Fig. 4 and F and F' in Fig. 1. The 5 number of lines in such a picture is, therefore, doubled. As shown in Fig. 4 the adjustment of the optical system is made such as to form an image of one half size so that two lines occupy the space previously 10 taken up by one. The grain of the picture is then considerably finer than in pictures composed of single lines. This results not only in duplicating the number of lines per inch in the reproduction, but actually increases 15 the resolving power of the optical system. This is seen by comparing the lines in Fig. 4, which are composed of B and A', B' and C, and C' and D. The line B'-C of Fig. 4 is the same as the line B-C of Fig. 20 3, but there is no duplication of this line, since the half line B, which is identical with B', is associated with the half line A'. In the same way the half line C', identical with C, is associated with the half line D. 25 It is, therefore, seen that no two lines are alike and four such lines are formed instead of two. Upon examination, it is noted that the light areas between the successive dark lines are duplicated while the dark 30 areas are all different. Thus it will be seen that the light areas H and H' are identical, and K and K' are identical. From this it is apparent that the resolving power of the 35 optical system is increased by 50%.

In the case of an optical system, as described in applicant's Patent No. 1,683,976, referred to above, the reproduction is composed of a series of exposures along the trace which correspond in density to the full line 40 in Fig. 6. Such an optical system is illustrated in Fig. 5. In this case the string of the light valve vibrates in the direction of the trace on the recording film. For the purpose of illustration the double image element is shown as a so-called bi-prism formed integral with the lens 22 so that the combination 45 as shown in Fig. 5 has a curved lens surface 23 facing the recording film and an opposite face composed of two sections 24 and 25 at a small angle to each other. Such a lens forms two distinct images of the light valve on the recording film. When a double image element is employed in combination with the optical system of Fig. 2 successive 50 images are displaced by half an exposure interval, so that instead of simple exposures a, b and c, shown in full lines in Fig. 6, there is formed on the recording element a series of overlapping or double exposures 55 corresponding to a-a', b-b', c-c', etc., the second exposure being indicated by the broken line in Fig. 6. The resulting exposure has none of the grained effect of the pictures formed by other methods of reproduction. By overlapping the exposures the 60

"no exposure" portion between half cycle exposures are eliminated forming a true half-tone picture similar to the original.

The double image forming elements are interchangeable in the optical systems shown 70 in Figs. 1 and 5. That is a bi-prism, a split-lens, or a piece of Iceland spar may be used in either system as desired, or any other double image forming element or combination 75 may be employed.

In order to insure the proper positioning of successive overlapping images in using Iceland spar the crystal is mounted so that it may be turned about its axis. In this way the separation of the ordinary and the extra- 80 ordinary ray may be varied at will. As illustrated in Fig. 1 the crystal is mounted on a pivot 27 and adjusted to the proper angular position by screw 28.

Another means for producing a somewhat 85 similar effect is illustrated in Fig. 7. In this case a cylindrical lens is employed for distorting the image by spreading the beam of light along the trace instead of focusing at a point. In this case the successive exposures overlap, as shown in Fig. 8, so that the grained effect is lost. Other means than those specifically described above may be employed for doubling the image or overlapping successive images, without departing 90 from the spirit and scope of the invention. The invention is not in any way limited for use with the optical systems referred to in applicant's patents, but is capable of use in connection with any suitable type of record- 95 ing or reproducing mechanism, whether used in picture transmission or in any other manner for reproducing pictures, writing, etc.

What is claimed is:

1. An optical system for use in picture transmission comprising a double light refracting image forming element.
2. The combination with light sensitive means of electro-optical means for exposing said light sensitive means in successive duplicate sets of lines to cause adjacent non-duplicate lines to overlap.
3. The combination with light sensitive means of electro-optical means for exposing said light sensitive means in adjacent pairs of lines to cause adjacent lines of said adjacent pairs to overlap.
4. In an optical system comprising a light source, a recording element, and a light valve having a variable aperture for controlling the light falling upon the recording element, means for forming an image of said light valve aperture on the recording element and other means for doubling the image formed.
5. In an optical system for picture transmission apparatus, means for forming an image on a recording element, and a piece of Iceland spar for doubling said image.
6. The method of producing pictures which comprises modulating a beam of light, form-

ing an image in accordance with said beam, doubly refracting the image formed, and recording impressions of said refracted images to form a picture.

5 7. In an optical system, a light source, means for forming successive images of said light source in pairs on a recording film, and means for causing overlapping of images of adjacent pairs on the recording film.

10 8. In an optical system a double image forming element, and means to adjust the angle of incidence of rays of light on said double image forming element, whereby the separation of the emergent rays is controlled.

15 9. The combination with a picture receiv-

ing surface of electro-optical means for producing thereon a picture composed of a plurality of similar series of exposures.

10. In an electro-optical system for producing an image of an object, means upon 20 which the image is to be produced, and electro-optical means for simultaneously affecting a plurality of non-contiguous elemental areas of said first mentioned means in accordance with the tone value of a single ele- 25 mental area of said object.

In witness whereof, I hereunto subscribe my name this 2 day of March A. D., 1925.

HERBERT E. IVES.
